UNITED STATES PATENT OFFICE.

LOUIS BURKE, OF NEW YORK, N. Y.

PERMUTATION ADJUSTER.

Application filed January 30, 1924. Serial No. 689,520.

To all whom it may concern:

Be it known that I, LOUIS BURKE, a resident of New York, New York County, and New York State, and a citizen of the United States, have invented certain new and useful Improvements in Permutation Adjusters, of which the following is a specification.

This invention relates to permutation adjusters adapted to bring about the contact 10 or to influence a magnetic field to a greater or less degree, to strengthen or decrease radio waves or for similar purposes. The object of the invention is to provide intermediate means or gearing between dials so 15 that when one is rotated the other may be also rotated at a much slower rate so that very delicate adjustments can be made.

These and other details and objects of the invention are more fully described in 20 the following specification, set forth in the appended claims and illustrated in the accompanying drawings, wherein:

Figure 1 is a face view of the improved permutation dials.

Fig. 2 is a face view of the lower dial 25 detached.

Fig. 3 is an interior view of the upper and smaller dial.

Fig. 4 is a vertical sectional view on the 30 line 4-4 of Fig. 3.

Fig. 5 is a vertical sectional view showing a modified construction.

This device is applicable to many forms 35 of scaled dials adapted to be set to secure delicate and accurate readings, measurements or adjustments and as shown in the drawings and as hereinafter described, it is best adapted for application to the attuning shaft of a radio wave receiver.

In addition to the dial 10 that is common 40 to these instruments a second dial 11 is provided and mounted concentric with the first dial. The second or upper dial comprises a box or housing of depending flange 12 that fits over a hub 13 on the dial 10 that has a circumferential groove 14 adapted to receive the inner ends of screws 15 which permits of the independent rotation of the dials while they are secured together.

At the center of dial 10 is secured the 50 attuning shaft 16 while through a central opening in the dial 11 extends a stem 17 of a knob 18 that also carries at its lower end the pinion 19. This pinion 19 meshes with 55 an idler 20 journalled on a stud on the lower side of the dial and which drives a

pinion 21 that is secured to a bevelled gear 22, the two being journaled in the bracket 23 and the latter gear wheel 22 meshes with a similar wheel 24 secured on a shaft that is 60 journaled in a bracket 25 and also carries the worm 26.

On the upper face of dial 13 are a series of pegs 27 arranged circularly and that are concentric with the opening in which the 65 shaft 16 is located and these pegs act as teeth which the worm 26 engages so that when the knob 18 is rotated the train of gear wheels above described will eventually rotate the dial 10, but on account of the 70 disproportion of the wheels 20 and 21 and the worm 26 and the pegs 27 the speed is geared down considerably.

If, therefore, the dials 10 and 11 are 75 initially set at the same number and it is desired to rotate the shaft 16 or arms thereon, a very small but predetermined distance, the knob 18 is turned and the disc 10 is slowly moved until the predetermined reading or number reaches the desired point. 80

To accomplish this adjustment the box 12 must be held by one hand while the other manipulates the knob, the original setting of the base dial having been made by the 85 said box and all of the parts moved together.

In the modified form shown in Fig. 5 the 90 gearing to drive the worm 26 is identical with that already described but the dial 13 has an upright flange 28 having horizontally disposed pegs 29 and the location of the worm 26 ensures its engagement with the pegs to rotate the dial 13.

It is obvious that the parts may be otherwise arranged or modified without departing 95 from the essential features above described or from the scope of the appended claims.

What I claim as new is:

1. In permutation adjusters, the combination of a dial comprising a base, a second dial comprising a box-like housing, means for securing the dials together and permitting independent movement, gearing within the box and adapted to cause one of the dials 100 to move the other, and a knob outside of the box adapted to actuate the gearing to move one dial independently.

2. In permutation adjusters, the combination of a dial having a scale, comprising a 110 base and carrying a shaft, a second dial having a similar scale as the first and compris-

ing a housing, means connecting the dials so as to permit independent action, gearing within the housing and adapted to rotate the dials together, and a knob outside of the housing adapted to actuate the gearing.

3. In permutation adjusters, the combination of a dial secured to the end of a shaft, a smaller dial having a housing that is secured to the first dial, a knob having a stem adapted to pass through an opening in the smaller dial, a pinion on the inner end of the stem, teeth on the first dial, and intermediate gearing between the pinion and the teeth adapted to cause the dials to move together or to rotate the larger dial only when the knob is turned.

4. In permutation adjusters, the combination of a shaft, a dial secured to the shaft, a second dial having a depending flange to constitute a housing, means for swivelling the housing to the first dial, teeth on the inner face of the first dial, a worm gearing with said teeth, a stem having a knob on its outer end and a pinion on its inner end and journaled in the second dial, and intermediate gearing between the pinion and the worm and adapted to cause the dials to move together or to move the first dial only when actuated by the knob.

In testimony whereof I hereunto affix my signature.

LOUIS BURKE.
